UNITED STATES PATENT OFFICE.

JOHN Y. KING, OF NEW YORK, N. Y., ASSIGNOR TO KING OXYGEN VALVE, INC., A CORPORATION OF NEW YORK.

COMBUSTION-ACCELERATOR.

1,177,113.

Specification of Letters Patent. Patented Mar. 28, 1916.

Application filed August 17, 1915. Serial No. 46,001.

To all whom it may concern:

Be it known that I, JOHN Y. KING, a citizen of the United States, residing at New York, in the county of New York and State 5 of New York, have invented new and useful Improvements in Combustion Accelerators, of which the following is a specification.

My invention relates to new and useful improvements in combustion accelerators, 10 and has for its object to provide an exceedingly simple and effective device of this character which may be readily and quickly applied to the lid supporting bridge of a stove or range; so that air may be taken into 15 the same and raised to a very high temperature, and then delivered to the fire above the same where this superheated air will commingle and mix with the flame from the fire and the gases thrown off thereby, so as 20 to greatly accelerate the combustion and consume the smoke producing elements.

A further object of the invention is to provide a combustion accelerator which will be supported by the bridge and depend 25 therefrom so that the air therein will be raised to a high temperature, before being delivered through outlet openings in the form of small perforations or slots at the ends of the device.

30 A still further object of the invention is to provide a supporting means having an inlet opening therethrough whereby the atmospheric air will be drawn into the device by the draft through the stove and chimney.

35 A still further object of the invention is to provide a device for attachment to the bridge which is a part of the stove seldom removed or disturbed, said bridge, because of its downwardly projecting flanges which 40 hold the stove lids, protecting the attached device against disturbances caused by attending to the fire.

45 A still further object of the invention is to provide a device of the title stated which when exteriorly considered is arcuate transversely, so that a very small surface of the device is in contact with the supporting bridge, thereby permitting the heat to circulate entirely around the device and come 50 in contact with nearly the entire surface of the supporting bridge which will tend to more quickly heat the air within the device and prevent the bridge from being cooled off, which would make this portion of the 55 stove useless.

With these ends in view, this invention

consists in the details of construction and combination of elements hereinafter set forth and then specifically designated by the claim.

60 In order that those skilled in the art to which this invention appertains may understand how to make and use the same, I will describe its construction in detail, referring by numerals to the accompanying drawing forming a part of this application, in which—

Figure 1, is a plan view of a stove or range showing the position of this device in dotted lines. Fig. 2, is an enlarged side 70 elevation of my improved combustion accelerator showing the supporting bridge in section. Fig. 3, is a bottom view thereof. Fig. 4, is a plan view of the combustion 75 accelerator removed from the supporting bridge. Fig. 5, is a section at the line 5—5 of Fig. 4; and Fig. 6, is an end view thereof, the supporting screw being removed.

In carrying out my invention as here embodied 2 represents a stove or range of any 80 suitable and well known construction or configuration, and used for heating or cooking purposes, and the top of the stove is provided with the supporting bridge 3 which assists in supporting the stove lids or 85 eyes 4 by means of the arcuate lid flanges 5 which depend from opposite edges of the supporting bridge.

In the supporting bridge is formed an 90 opening 6 preferably of two diameters, the larger diameter adapted to receive the head 7 of the supporting screw 8, so that the outer face of the head of said screw will be flush with the outer surface of the supporting bridge to eliminate projections which 95 are objectionable because of their interference with cooking utensils placed upon the stove. This screw is provided with a central opening 9 passing entirely therethrough, and the head of said screw has slots or 100 grooves 10 formed therein in communication with the opening 9.

11 denotes a casing comprising a flat bottom wall 12, an arch wall 13, and end walls 14, the arch wall where it connects with the bottom wall and intermediate its ends being concavo-convex, so as to conform approximately to the shape of the supporting bridge 3. The arch wall of the casing is provided with a boss 15 in which is formed 110 a threaded inlet opening 16 into which the screw 8 is threaded for supporting the cas-

ing from the supporting bridge 3, and in order to prevent the casing from moving about I provide a pair of spaced integral upwardly projecting lugs 17 formed with 5 the arch wall adjacent one end of the casing and situated some distance from the supporting screw, said lugs adapted to engage the underface of the supporting bridge 3, and because of the unevenness of the under 10 or inner face of the supporting bridge, said lugs will be prevented from sliding or moving about over the surface of the supporting bridge when the casing is drawn tightly against the supporting bridge. The boss 15 15 and lugs 17 space the casing from the supporting bridge for the passage of the heat, whereby all of the walls of the casing will be heated, and so that the proper temperature will be maintained upon the supporting 20 bridge, whereby this part of the stove may be used for cooking purposes as well as any other portion thereof.

The air after passing into the heating chamber 18 in the casing and being raised to 25 a high temperature is then sprayed or projected into the flame through the outlet openings 19 preferably formed adjacent each end of the casing, either in the bottom wall 12 or a portion of the arch wall 13 or both, 30 and these outlet openings may be in the form of small holes or slots.

In practice a hole 6 is formed in the supporting bridge 3 or if found desirable any other portion of the stove and the casing 35 11 is placed beneath the same, so that the threaded opening 16 is in alinement with the opening 6, at which time the screw 8 is passed through the opening 6 and threaded into the opening 16, which will draw the 40 casing against that part of the stove to which it is attached, where it will be firmly held against accidental displacement.

In placing the screw 8 in position the slots 10 may be used as a screw driver slot. 45 When the device is properly placed in position, atmospheric air will be drawn into the heating chamber 18 through the inlet opening 9 in the screw 8, where it will be raised to a very high temperature which 50 will also increase the pressure, said pressure causing the super-heated air to be forced through the outlet openings 19 into the flame of the fire, thereby adding sufficient oxygen to the mon-oxid thrown off 55 by the fire to produce a combustible gas which will immediately ignite and consume the foreign matter which generally passes up the chimney as smoke, and the combustion of this gas will also raise the temperature 60 within the stove so as to greatly increase the efficiency of said stove.

Because of the construction of the casing 11 the heat is allowed to pass entirely around

said casing and to also come in contact with the supporting bridge 3, thus effectually 65 heating the air within the heating chamber 18 as well as the supporting bridge 3, which is essential to the efficiency of the stove, for if any considerable amount of the surface of the supporting bridge is covered by the device, the temperature of said supporting bridge would be lowered and the efficiency 70 of the stove greatly decreased.

As hereinafter described the outer face of the head 7 of the screw 8 is preferably 75 flush with the outer face of the supporting bridge 3, so that there are no projections to interfere with the cook-utensils upon the stove and the head of said screw is provided with slots or grooves 10 leading from 80 the outer circumference thereof to the inlet opening 9, so that if a cooking utensil is placed upon the stove and covers the inlet opening 9, but not both of the grooves 10, the air will pass through said uncovered 85 groove 10, then through the inlet opening 9 and into the heat chamber 18.

Of course I do not wish to be limited to the exact details of construction as herein shown, as these may be varied within the 90 limits of the appended claim without departing from the spirit of my invention.

Having thus described my invention, what I claim as new and useful, is—

A combustion accelerator comprising a 95 casing consisting of a flat or straight bottom wall having outlet openings adjacent each end, end walls and an arch wall, said arch wall being concavo-convex where it joins the bottom wall and provided with a threaded opening leading to the interior of the casing, upwardly projecting integral lugs formed with the arch wall of the casing, a supporting bridge to which the casing is to be secured, said supporting bridge having 100 an opening therein of two diameters, and a screw provided with a head and having a longitudinal inlet opening passing therethrough, said screw adapted to be passed through the opening in the supporting 110 bridge, and mounted in the threaded opening in the casing for drawing the casing against the underface of the supporting bridge, the outer face of said screw lying flush with the outer surface of the supporting bridge, the head of said screw having grooves therein leading from the outer 115 circumference of the head to the inlet opening.

In testimony whereof, I have hereunto 120 affixed my signature in the presence of two subscribing witnesses.

JOHN Y. KING.
